UNITED STATES PATENT OFFICE.

MILTON R. THURBER AND RICHARD B. BROCKWAY, OF SCRANTON, PA.

CAR-AXLE LUBRICATOR.

SPECIFICATION forming part of Letters Patent No. 335,163, dated February 2, 1886.

Application filed November 3, 1885. Serial No. 181,785. (No model.)

To all whom it may concern:

Be it known that we, MILTON R. THURBER and RICHARD B. BROCKWAY, of Scranton, in the county of Lackawanna and State of Pennsylvania, have invented certain new and useful Improvements in Lubricators; and we do hereby declare the following to be a full, clear, and exact description of the same, reference being had to the accompanying drawings, forming a part of this specification, and to the figures and letters of reference marked thereon.

Our invention has for its object to improve the construction of lubricators for oiling the journals of railway-car axles; and it consists in a certain improved construction, which we will now proceed to describe.

In the accompanying drawings, Figure 1 is a side view of a car-axle-lubricator constructed in accordance with our invention. Fig. 2 is a view with the casing broken away and partly in section; Fig. 3, a view of the bearing block or "brass;" Fig. 4, a view of the improved oil-conveyer.

Similar letters of reference in the several figures indicate the same parts.

A represents an ordinary car-axle, and B the bearing-box, constructed with its outer portion square, as shown, and provided at its inner or rear end with an enlarged circular portion, B'.

C is the bearing block or brass, placed in the upper part of the square portion of the box and resting upon the journal of the axle, provided with two inclined slots or grooves, c—one on each side—extending from the middle of the rear end to about the middle of the lower side or bearing portion of the block.

The round portion B' at the end of the box contains a recess or chamber, D, communicating with the chamber in the square portion of the box at the bottom, and the end of the brass or bearing-block C projects into it at the upper side.

E represents a "wiper" mounted upon the axle, consisting of a plate having one or more arms, (we have shown two in the drawings,) having near their ends slight depressions or recesses e, as shown, for conveying the oil from the bottom of chamber D to the bearing-block. The plate has a perforation near its

center, through which the axle extends, and one or more lugs, e', projecting inwardly, entering slots a in the axle, and securing the plate to it, so that it will revolve with the axle 55 and within the chamber D, and will also, in revolving, pass across the end of the bearing-block C, as shown.

In the upper side of the portion B' of the box is an opening provided with a hinged door, F, for the purpose of permitting the ready application and removal of the wiping-plate E. In order to apply the said plate, it is necessary to withdraw the axle from the box and remove the bearing-block, insert the wiping-plate through the door F into the chamber, and then insert the axle through the perforation in the plate, causing the projections in the latter to register with the grooves in the former.

When the axle is in place, the bearing-block is put in, and the device is ready for operation.

The space beneath the bearing-block is to be filled, if desired, with wool or waste, as usual, and a small partition, G, is provided near the end of the chamber, to prevent the waste or wool from working down into the chamber D.

The operation is as follows: The oil is 80 poured into the box through the door x at the front, and collects in the bottom of the chamber D, where it is taken up in the recesses e of the wipers as the axle revolves, and is wiped off into the slots or grooves c on the sides of 85 the bearing-block and runs down said slots onto the journal of the axle, as will be readily understood. The oil dripping off the journal runs back into the chamber D, and is again wiped up into the slots in the brass, as before. 90 Thus it will be seen that the journal will be supplied with oil as long as the car is in motion, and that no oil is wasted, but it is used again and again, and positively fed to the journal until evaporated or leaked out, and is 95 not allowed to stand and harden, as is often the case where wicking is depended upon to supply it to the journal.

The herein-described lubricator can be made very cheaply, and applied readily to a car, no 100 more labor or skill being required than in the application of an ordinary car-axle box, while

its operation is positive, and its simple construction renders it less liable to get out of order.

We are aware that lubricators for car-axles have been made consisting of a lifting device for dipping up the oil and pouring it into a receptacle made in the upper side of the bearing-block, which latter is provided with perforations extending through it; but the advantages of our device over such constructions as these are obvious.

We claim as our invention—

1. The combination, with the axle and the plate mounted thereon, having the arms and the depressions or recesses therein, of the bearing-block having the grooves in its sides extending from about the middle of one end to the lower side, substantially as described.

2. The combination, with the axle having the grooves, the plate mounted thereon having the projections corresponding to the

grooves in the axle, and the arms provided with the depressions or recesses in their ends, of the bearing-block having the grooves in its sides, substantially as described.

3. The combination, with the box or receptacle, and the chamber D at its end, having the opening and door in its upper side, of the axle, the removable plate or wiper mounted on the axle, and the bearing-block provided with the grooves in its sides, substantially as described.

4. The improved bearing-block for car-axles, having the inclined grooves on its sides extending from about the middle of one end to the lower side of the block, substantially as described.

MILTON R. THURBER.
RICHARD B. BROCKWAY.
